(57) **CLAIM**

The ornamental design for a hammer tacker grip, as shown and described.

DESCRIPTION

FIG. 1 is a top perspective view of the hammer tacker grip showing our new design;

FIG. 2 is a top plan view thereof;

FIG. 3 is a left side view thereof, the right side being a mirror image of the left side;

FIG. 4 is a bottom plan view thereof;

FIG. 5 is a front elevational view thereof; and,

FIG. 6 is a rear elevational view thereof.

The broken line portions of the drawings are for illustrative purposes and form no part of the claimed invention.
